LAMP FILAMENT SUPPORT AND CONNECTION

Irving H. Van Horn, East Cleveland, Ohio, assignor to General Electric Company, a corporation of New York

Application November 30, 1944, Serial No. 565,825

5 Claims. (Cl. 176—39)

1

This invention relates to electric lamps and filament mounts, and especially to supports and current connections for filaments. The invention is here illustrated and explained as embodied in end supports which also serve as current supply connections, though it might also be applied to supports that sustain an intermediate portion of a filament, or do not carry current, or both. The filament mount here shown is of a concentrated coil type; but the invention is not limited to any particular type of mount. Various features and advantages of the invention will become apparent from the description of species and forms of embodiment, and from the drawings.

In the drawings,

Fig. 1 is a side view of a biplane coiled filament mount, for an incandescent lamp, that conveniently embodies the invention, portions of the lamp bulb being also shown.

Fig. 2 is a partly sectional view, on a larger scale, illustrating the attachment and electrical connection of a current lead and support to a filament; and

Fig. 3 is a similar view illustrating a different form of construction.

The mount here illustrated is that of a projection lamp of moderately high wattage, comprising a filament of tungsten wire coiled in a number of upright sections 1 that are interconnected by intermediate uncoiled U-portions or bights 2. The coils 1 may be staggered so as to lie alternately in two parallel planes. The supporting structure of the mount comprises leadwires 3, 3 sealed through the pressed seal 4 of an ordinary stem flare portion 5 of the lamp envelope. These leads 3, 3 are shown as offset outward at 6, 6, and then bent inward at 7, 7 near their upper ends. Long upright side sections 8, 8 of the leads 3, 3 (opposite and above and below the filament coils 1) may consist of refractory metal like molybdenum interposed between lengths of ordinary metal like nickel, butt-welded to the ends of the molybdenum. For engaging and holding the filament bights 2, there are upper and lower (molybdenum) wire hooks 9, 10 whose ends are fused into the sides of upper and lower vitreous cross-bars 11, 12. The upper bar 11 is supported by wires 13 fused into its lower side near its ends and welded to the inbent upper lead portions 7, 7, and the lower bar 12 is supported by bent wires 14 fused into its upper side near its ends and welded to the lower lead portions 6, 6. Bent spacing wires 15 fused into the lower side of the upper bar 11 between hooks 9 and wires 13 may be pro-

vided for engaging the lamp bulb and bracing the mount transversely therein.

To hold the coiled end sections 1 of the filament taut or under suitable tension, and to connect the current leads 3, 3 to these ends, supporting connections 16, 16 according to my invention are shown. In the form here illustrated, each of these comprises a spud like member 16 of suitable size wire provided with a helical screw thread and having one end screwed into and completely through a helically coiled filament end portion 17, which may be connected to the adjacent coiled section 1 by an uncoiled length 18. The other end of the member 16 is shown welded to the portion 7 of the corresponding lead 3. The coil 17 is not only in screw mesh with the threads of the member 16, but in definite frictional engagement with them. To this end, the coil 17 may be coiled to a size slightly smaller than that of the threads of member 16, so that the coil will elastically grip the member when the latter is screwed into the coil. When the member 16 is screwed completely through the coil 17, the frictional contact of the screw threads in the coil 17 short-circuits all the coil turns, so that a definite length of filament exclusive of the coils 17, 17 is in circuit between the connectors 16, 16. The spuds 16, 16 may preferably be welded to the lead portions 7, 7 after being screwed into the filament coils 17, 17, which may conveniently be done before the filament is placed on the hooks 9, 10.

As shown in Fig. 2, the screw thread on the member 16 consists of a coil of wire 19 tightly fitting around and frictionally gripping the member. Although this is not essential, the wire 19 is shown finer than the filament wire, as well as finer than the member 16. The wire 19 may either be wound on the member 16 under suitable tension, or may be wound on a mandrel slightly smaller than the member 16, and then removed and slipped over the latter, so as to grip it elastically.

As shown in Fig. 3, the screw thread on the member 16 is formed integral with the latter, by a screw-cutting operation.

Both types of screw connector 16 may be of molybdenum, including in the Fig. 1 type the winding 18 as well as the member 16. In both cases, the pitch of the screw threads of member 16 may be approximately the same as that of the coacting filament coil 17. In manufacture, it is convenient and economical to screw-thread long lengths of wire and cut them up into Fig. 3 type spuds 16 of suitable length; or to wind long lengths of unthreaded wire 16 with the wire 19,

heat-treat the same to set the coil 18, and then cut the overwound wire up into proper spud lengths of Fig. 2 type.

What I claim as new and desire to secure by Letters Patent of the United States is:

1. An electric lamp comprising a mount including supporting structure and a coiled filament, and a spud for tensioning coil convolutions of said filament attached to said supporting structure and provided with screw threads in screw mesh and frictional engagement with other coil convolutions of said filament, the said screw mesh frictional interengagement providing the sole electrical and mechanical connection of the spud to the filament.

2. In a filament mount, the combination with a support of a spud attached at one end to said support and provided with screw threads on its other end, and a filament having a helically coiled portion in screw mesh and frictional engagement with the threads on the said other end of said spud, the said screw mesh frictional interengagement of the said screw threads and helically coiled portion of the filament providing the sole electrical and mechanical connection of the spud to the filament.

3. In combination, a filament support comprising a mandrel member, a helical wire coil having convolutions fitted around and directly gripping said member, thus forming screw threads on said member, and a filament having a helically coiled portion with its convolutions engaged between and in screw mesh with those of said first coil, the said screw mesh interengagement of the said wire coil and helically coiled portion of the filament providing the sole electrical and mechanical connection of the filament to the mandrel member.

4. In an electric incandescent lamp, the combination of a lead-in conductor, a spud secured at one end to said conductor and provided with screw threads on its other end, and a filament having a coiled end portion screwed tightly over the threaded end of said spud, the screw mesh interengagement of the said screw threads and coiled end portion of the filament providing the sole electrical and mechanical connection of the spud to the filament.

5. In an electric incandescent lamp, the combination of a lead-in conductor, a spud secured at one end to said conductor and provided with screw threads on its other end, and a filament having an end coil portion coiled to a size slightly smaller than the threads on said spud and screwed thereover, the screw mesh interengagement of the said screw threads and end coil portion of the filament providing the sole electrical and mechanical connection of the spud to the filament.
